Primary Examiner — Darlington Ly

(74) Attorney, Agent, or Firm — Woodard, Emhardt,
Moriarty, McNett & Henry, LLP(57) **CLAIM**

The ornamental design for a torque wrench, as shown and described.

DESCRIPTION

FIG. 1 is a top, rear, and right side perspective view of a torque wrench showing my new design;

FIG. 2 is a right side elevation view thereof;

FIG. 3 is a left side elevation view thereof;

FIG. 4 is a bottom plan view thereof;

FIG. 5 is a top plan view thereof; and,

FIG. 6 is a rear elevation view thereof.

The broken lines in the drawings illustrate portions of the torque wrench that form no part of the claimed design.

1 Claim, 5 Drawing Sheets(56)
